UNITED STATES PATENT OFFICE

WILBERT L. MARTIN, OF TULSA, OKLAHOMA

APPARATUS FOR FLOWING WELLS BY AIR LIFT

Application filed February 1, 1928. Serial No. 251,036.

My invention relates to apparatus for flowing wells by air lift, and has for its principal objects to conserve the so-called natural rock pressure so that it may be employed for maintaining a column of fluid above the level normally maintainable by the rock pressure, and to provide a continuous flow of the oil by introduction of gas under pressure into the tubing at various elevations, whereby a fluid 10 column is maintained by the natural pressure and stepped upwardly in continuous flow by the artificial pressure.

In accomplishing these and other objects of the invention I have provided improved 15 details of structure, the preferred forms of which are illustrated in the accompanying drawings, wherein:

Fig. 1 is a perspective view of an oil well equipped with my improved apparatus, the 20 well and its casing being in central vertical section.

Fig. 2 is an enlarged detail perspective view of the apparatus showing the tubing in vertical section, part of the enclosed apparatus being broken away for better illustration.

Referring in detail to the drawings:

1 designates a well hole having a well pocket 2 in a strata of oil bearing sand 3, the 30 well hole being lined with casing 4 supported upon the cap rock 5 by the casing shoe 6, the casing being capped and sealed by a casing head 7. Suspended within the casing is a well tubing 8 having the usual strainer 9 at its 35 lower end extending into the pocket 2, the upper end of the tubing extending through the casing head 7 and being provided with a T fitting 10 with which the flow pipe 11 is connected. An inlet pipe 12 for gas under 40 pressure, which will be referred to as air, is introduced into the casing head whereby air is admitted to the casing to lift the fluid received in the tubing through the strainer for 45 delivery through the pipe 11 to storage means (not shown).

Supported by and in the casing 8 near the bottom of the well is a packer 13 providing upper and lower chambers 14 and 15 in the 50 casing and sealing off the natural rock pres-

sure within the lower chamber to conserve said pressure and to render it effective for lifting the fluid in the tubing, and also for preventing back pressure on the fluid by artificial pressure medium introduced into the 55 casing.

In the early stages of the flowing of wells natural rock pressure lifts the column of fluid to a relatively high level in the tubing, from which level the artificial pressure 60 medium may pick it up and urge it to the top of the well. In order to assist the natural rock pressure to maintain a fluid column at a desired level after the latter has become partially exhausted, I have provided for the 65 introduction of air under pressure at a point adjacent the bottom of the tubing, means therefor comprising a transverse, tubular inlet nipple 16 in the tubing having inlet ports 17 in the walls of the tubing, and a pipe 18 70 connected into said nipple extending downwardly in the tubing to a level in the pocket 2 preferably slightly above the level of the oil sand, whereby air under pressure is conducted from the upper casing chamber for 75 discharge into the tubing below the level of the fluid maintained by the rock pressure. Screw-threaded on the lower end of the pipe 18 is a conical cap 19 having a distributing chamber 20 and ducts 21 leading upwardly 80 and angularly from the chamber for delivery into the interior of the tubing, whereby air under pressure passing from the casing into the pipe will be discharged upwardly against the column of fluid in the tubing to assist the 85 natural rock pressure in initially lifting the oil through the tubing. The cap member is provided with exterior grooves or channels 22, whereby fluid admitted to the tubing through the strainer portion thereof is permitted to pass the cap.

Positioned in the tubing above the transverse inlet nipple member 16 are nozzles 23 angularly directed upwardly toward the center of the tubing, having inlet ports 24 for 95 admitting air under pressure from the casing into the tubing; the inner ends 25 being restricted slightly to provide stop flanges for retaining the back-check ball valves 27, which seat downwardly on seats 28 in the nozzle 100

channels, for preventing return flow of fluid from the tubing into the casing.

In practicing the invention, the apparatus being installed as described, air under pressure admitted to the casing moves simultaneously through the ports of the inclined inlet nozzles 23 and inlet nipple 16. Air entering through the nipple is conducted into the cap adjacent the oil pocket and, being emitted therefrom, assists the natural rock pressure in raising the oil in the tubing to a level where it may be acted upon by the air entering the tubing through the nozzles 23 to lift the oil through the tubing to the upper end thereof, from which it is discharged into the flow pipe and conducted to storage. The natural rock pressure being retained beneath the packer is, therefore, permitted to act upon the oil in the pocket to lift the oil to the limit of its ability, and the air under pressure conducted by the depending pipe into the lower end of the tubing picks up the oil at any level to which it has been raised by the rock pressure and elevates it further to a position where it may be acted upon by the primary pressure inflow.

What I claim and desire to secure by Letters Patent is:

1. In combination with well casing, a packer in the casing, tubing extending through the packer, a conduit in the tubing communicating with the casing above the packer and terminating in the tubing below the packer, a cap on the lower end of the conduit having a distributing chamber and ducts leading from said chamber to communication with the casing below the packer, nipples in the tubing communicating with the casing above the packer, and means for delivering air under pressure to the casing above the packer.

2. In combination with well casing, a packer in the casing, tubing extending through the packer, a conduit in the tubing communicating with the casing above the packer and terminating in the tubing below the packer, a cap on the lower end of the conduit having a distributing chamber, having ducts leading from said chamber to communication with the casing below the packer and having exterior passageways for well fluid, nipples in the tubing communicating with the casing above the packer, and means for delivering air under pressure to the casing above the packer.

3. In combination with well casing, a packer in the casing, tubing extending through the packer, a conduit in the tubing having a T-head communicating with the casing above the packer and a body portion terminating in the tubing below the packer, a cap on the lower end of the conduit having a distributing chamber and ducts leading from said chamber to communication with

the casing below the packer, nipples in the tubing communicating with the casing above the packer, and means for delivering air under pressure to the casing above the packer.

In testimony whereof I affix my signature.

WILBERT L. MARTIN.
